(57) **CLAIM**

An ornamental design for a hockey puck bottle opener, as shown and described.

DESCRIPTION

FIG. 1 is a perspective view of a hockey puck bottle opener showing our new design;

FIG. 2 is a top plan view thereof;

FIG. 3 is a bottom plan view thereof;

FIG. 4 is a front view thereof;

FIG. 5 is a right side view thereof;

FIG. 6 is a rear view thereof; and,

FIG. 7 is a left side view thereof.

The broken lines in FIGS. 1 and 2 are included for the purpose of showing areas that form no part of the claimed design.

1 Claim, 5 Drawing Sheets
